LOESER KALINA, OF NEW YORK, N. Y.

WASHBOARD.

1,107,168.

Specification of Letters Patent.

Patented Aug. 11, 1914.

Application filed July 25, 1913. Serial No. 781,168.

To all whom it may concern:

Be it known that I, LOESER KALINA, a citizen of the United States, and a resident of the city of New York, borough of Brooklyn, in the county of Kings and State of New York, have invented a new and Improved Washboard, of which the following is a full, clear, and exact description.

The object of the invention is to provide a new and improved washboard, arranged to form a cover for a wash tub when the latter is not used, and to permit of conveniently removing the cover from the wash tub whenever it is desired to use the tub and the washboard for washing purposes. In order to accomplish the desired result use is made of two washboards hinged together at adjacent side rails to permit of folding the washboards one upon the other for rubbing on either face thereof and to allow of extending the washboards in the same plane to form a cover for the wash tub.

A practical embodiment of the invention is represented in the accompanying drawings forming a part of this specification, in which similar characters of reference indicate corresponding parts in all the views.

Figure 1 is a perspective view of the convertible wash tub cover and washboard shown in duplicate and in position on a two-compartment wash tub to form a cover for the same; Fig. 2 is an enlarged plan view of one of the covers in position on the wash tub; Fig. 3 is a face view of the convertible wash tub cover and washboard removed from the wash tub and with the washboard folded and fastened together to form a double washboard; Fig. 4 is a side elevation of one side of the same; Fig. 5 is a similar view of the other side of the same; Fig. 6 is a sectional perspective view of portions of the double washboards and showing more particularly the locking device for fastening the outer rails of the washboards together; Fig. 7 is a sectional plan view of portions of the folded washboards showing more particularly the hinge connection between the inner side rails the section being taken on the line 7-7 of Fig. 4; and Fig. 8 is a cross section of the folded washboards showing more particularly the coarse and fine corrugated rubbing surfaces of the two washboards, the section being taken on the line 8-8 of Fig. 3.

As shown in the drawings, use is made of two washboards A, A' having outer side rails B, B' and inner side rails B², B³, the washboards also having top rails C, C', and rubbing surfaces D, D' in the form of corrugated sheets of metal, of which the corrugations of one sheet are coarse and the corrugations of the other sheet are fine, to permit of washing coarse and fine clothes on the washboards. The washboards A, A' are further provided with soap boards E, E', and covering plates F and F' extending over the backs of the washboards, as plainly shown in Figs. 1 and 2, so as to form a smooth upper surface at the time the two washboards A, A' are in extended position and used as a cover on the wash tub, as shown in said Figs. 1 and 2.

The inner rails B², B³ of the washboards A, A' are connected with each other by a hinge G to permit of swinging the washboards either into a folded position, as shown in Figs. 3, 4, 5, 6, 7 and 8, or into a closed position with the washboards lying in the same plane, as indicated in Figs. 1 and 2. The outer rails B and B' of the two washboards A and A' are adapted to be fastened together by a locking device H whenever the washboards are in folded position, it being understood that the said hinge G and the said locking device H are provided with members forming extension legs for the washboards, as hereinafter more fully explained, the said members being also adapted to engage hooks I, I' held in recesses J', J² of the back board J of a wash tub K on which the washboards are used as covers when in extended position.

The hinge G is constructed as follows: The covering plates F, F' are provided with angular flanges F², F³ extending over the outer edges of the inner rails B², B³ (see Fig. 7) so as to form hinge leaves engaged by a pintle formed of two members G', G² in the form of return bent wire, and of which the pintle member G² is slidable lengthwise on the leaves by cutting out registering portions F⁴, F⁵ on the flanges F², F³ formed on the leaves, as plainly indicated in Fig. 4. By the arrangement described the member G² can be extended to form a leg for the folded washboard, but the outer bent portion of the said member G² is adapted to hook onto the hook I to form a hinge connection between the washboard A and the

back board J. The member G' is in the form of a link and is arranged at the upper portions of the washboards A and A', and the covering plates F, F' are provided with cut-out portions F⁶, F⁷ adjacent the upper and lower ends of the cut-out portions F⁴, F⁵. The outer bend of the member G' is outside the upper ends of the washboards A, A', while the inner bend is in register with the cutout portion F⁶, and the upper end of the member G² is likewise in register with the cut-out portion F⁶ at the time the said member G² is in innermost position, as indicated in Fig. 2. The cut-out portions F⁶, F⁷ permit the washboards A, A' to conveniently swing into closed position so that the covering plates F, F' overlie one the other. When the member G² is in withdrawn position, as shown in Figs. 3 and 4, then the upper end of the member G² is in register with the cut-out portion F⁷ to allow folding of the washboards A, A' with the legs in extended position. When the washboards are folded the upper end of the member G² abuts against the lower edges or shoulders formed by the covers at the bottom of the flanges F², F³ so that the member G² cannot be pushed upward as long as the washboards A, A' are in folded position. In order to accommodate the members G', G² on the rails B², B³ the latter are cut out as at B⁴, B⁵ (see Fig. 7). By providing the separate member G' the upper ends of the washboards A, A' are hingedly connected with each other at the time the other member G² is in withdrawn position, to provide a strong and durable hinge for the two washboards.

The locking device H is in the form of a rod H' mounted to slide in a guideway formed by a flange F⁸ extending from the covering plate F over the outer rail B, the other covering plate F' having a similar flange F⁹ extending over the outer rail B', as plainly indicated in Fig. 6. The rail B is provided with a cut-out portion B⁷ to accommodate the rod H', which latter has its lower end provided with a return bent portion H² adapted to engage a guideway formed by the flange F⁹ and the cut-out portion B⁶ formed on the outer rail B'. The return bent portion H² forms with the rod H' a hook adapted to hook onto the hook I held on the back board J, as previously described and shown in Figs. 1 and 2. The upper end of the rod H' terminates in a handle H³ terminating in a locking pin H⁴ adapted to engage the bearing formed by the flange F⁹ and the cut-out portion B⁶, it being understood that a portion F¹⁰ of the flange F⁹ is cut out for the entrance of the locking pin H⁴ (see Fig. 6). The flange F⁸ is provided at its upper end with a slot or cut-out portion F¹¹ to permit of sliding the rod H' up-

ward into retracted position after the rod has first been moved downward from the position shown in Fig. 6 to disengage the pin H⁴ from its bearing, and after the handle H³ has been given a quarter turn to completely free the pin H⁴ from its bearing. It is understood that when the pin H⁴ and the member H² engage the flange F⁹ the two washboards A, A' are held locked in doubled-up position at both top and bottom.

When it is desired to unlock the washboards, the operator first slides the handle H³ downward until the pin H⁴ extends within the cut-out portion F¹⁰, and then the operator turns the handle H³ over to the right to swing the pin H⁴ free of the flange F⁹ to allow the operator to push the handle H³ outward to move the rod H' upward thus moving the leg into retracted position. When the locking pin H⁴ is in engagement with the flange F⁹ the return bent member H² has its upper end extending into the bearing under the flange F⁹ so as to provide a strong leg for the middle portion of the side rails B², B³ of the folded washboards A, A' (see Fig. 5). It is understood that when the handle H³ is moved downward, as previously described, it disengages the pin H⁴ from the flange F⁹, and the free end of the return bent portion H² moves out of engagement with the flange F⁹, and when the rod H' is slipped upward as before mentioned then the return bent portion H² extends on the outside of the flange F⁹, as shown in Fig. 2.

For wash tubs K having two compartments, a cover is provided formed of two washboards for each compartment, and the two sets of washboards are made left-hand and right-hand so that the locking devices H are on the outer sides of the wash tubs K, to insure a close fit of the two sets of extending washboards at their inner and adjacent portions, as will be readily understood by reference to Fig. 1. When the two washboards are extended and used as a cover on the wash tub K, the cover can be readily swung into open or closed position over the corresponding compartment of the wash tub K. When it is desired to use the wash tub K and the washboards for washing purposes then the operator takes hold of the front end of the two washboards A, A' and imparts an outward pull to the same so that the two legs are pulled outward on account of being hooked onto the hooks, I, I', and then the operator lifts the legs off the said hooks I, I' and swings the washboard A upon the washboard A', after which the operator takes hold of the handle H³ and gives a quarter turn to the same so that the locking pin H⁴ and the doubled-up member H² move into alignment with their bearing under the flange F⁹. The operator now

pushes the handle H^3 outward so that the pin H^4 and the return bent portion H^2 engage the bearing under the flange F^6 to lock the two washboards together and to hold the 5 legs in extended position.

By the arrangement described the cover of the wash tub can be conveniently removed and used as a washboard. The space on the wall in the rear of the tub K can be 10 used for kitchen closets and the like, as indicated in Fig. 1 owing to the fact that the cover is not swung open when it is desired to use the tub for washing purposes but the cover is bodily removed.

Having thus described my invention, I 15 claim as new and desire to secure by Letters Patent:

1. In combination, two washboards hinged together at adjacent side rails to permit of 20 folding the washboards one upon the other or opening the washboards to extend in the same plane, each washboard having a rubbing surface, the said washboards in the folded position having their backs opposite each other and having their rubbing surfaces outside for use of either rubbing surface.

2. In combination, two washboards each 25 having a rubbing surface, a hinge connecting the inner side rails of the washboards with each other to allow of folding the washboards one onto the other with the rubbing surfaces exposed, the pintle of the said hinge being slid able in the direction of the length 30 of the washboards and the said pintle being adapted to extend beyond the lower ends of the washboards to form a washboard leg, and a locking device for locking the outer side rails of the washboards together at the 35 time the washboards are folded, the said locking device having a member slid able in one of the outer side rails to extend beyond the lower ends of the washboards to form another washboard leg.

3. In combination, two washboards each 40 having a rubbing surface, a hinge connecting the inner side rails of the said washboards with each other, the hinge having leaves attached to the said inner side rails, and a pintle formed of a return bent rod, the side members of which pivotally engage the 45 said leaves.

4. In combination, two washboards each 50 having a rubbing surface, a hinge connecting the inner side rails of the said washboards with each other, the hinge having leaves attached to the said inner side rails, and a pintle formed of a return bent rod, the side members of which pivotally engage the 55 said leaves, the said return bent pintle rod being slid able on the said leaves, and one of the bent ends of the pintle being outside of the 60

lower ends of the inner side rails of the washboards.

5. In combination two washboards each 65 having a rubbing surface, a hinge connecting the inner side rails of the said washboards with each other, the hinge having leaves attached to the said inner side rails, and a pintle formed of a return bent rod, 70 the side members of which pivotally engage the said leaves, the said leaves having spaced cut-out portions for engagement by the inner bent end of the pintle rod when the latter is in extended or folded position. 75

6. In combination two washboards each 80 having a rubbing surface, a hinge connecting the inner side rails of the said washboards with each other, the hinge having leaves attached to the said inner side rails, and a pintle formed of a return bent rod, the side members of which pivotally engage the said leaves, the said pintle rod and the said rails having means for holding the pintle rod against inward movement when extended and 85 at the time the boards are in folded position.

7. In combination, two washboards each 90 having a rubbing surface, a hinge connecting the inner side rails of the said washboards with each other, the hinge having leaves attached to the said inner side rails, and a pintle formed of a return bent rod, the side members of which pivotally engage the said leaves, the said return bent pintle being slid able on the said leaves and one of the bent 95 ends of the pintle being outside of the lower ends of the inner side rails of the washboards, the said leaves having spaced cut-out portions for engagement by the inner bent end of the pintle rod when the latter 100 is in extended or folded position the outer portion of the said pintle rod forming a washboard leg at the time the said pintle rod is extended, and a locking device for locking the outer side rails of the washboards 105 together at the time the washboards are doubled up, the said locking device having guideways attached to the outer side rails of the washboards, and a locking rod slid able in one of the guideways and having at 110 its outer end a return bent portion adapted to form a second washboard leg and to slidingly engage the outer end of the other guideway, the inner end of the said locking rod having a handle terminating in a pin 115 adapted to engage the other guideway.

In testimony whereof I have signed my name to this specification in the presence of two subscribing witnesses.
